Patented Nov. 15, 1921.

Charles J. Dodge ^{Inventor}
By his Attorney
Charles G. Hensley

UNITED STATES PATENT OFFICE.

CHARLES J. DODGE, OF BROOKLYN, NEW YORK.

DESIGN FOR A SOUND-AMPLIFIER.

59,625.

Specification for Design.

Patented Nov. 15, 1921.

Application filed August 30, 1921. Serial No. 497,064. Term of patent 7 years.

To all whom it may concern:

Be it known that I, CHARLES J. DODGE, a citizen of the United States, and a resident of the borough of Brooklyn, city and State of New York, have invented a new, original, and ornamental Design for Sound-Amplifiers, of which the following is a specification, reference being had to the accompanying drawing, forming part hereof.

Figure 1 is a side elevation and Fig. 2 is a plan view of a sound amplifier, showing my new design.

I claim:

The ornamental design for a sound amplifier as shown.

CHAS. J. DODGE.
